DESIGN FOR A BELT

James Samuel Ashdowne, Detroit, Mich., assignor to Joseph Buegeleisen Co., Inc., Detroit, Mich.,
a corporation of Michigan

Application September 16, 1946, Serial No. 133,353

Term of patent 14 years

(Cl. D3—10)

To all whom it may concern:

Be it known that I, James Samuel Ashdowne, a citizen of the United States of America, residing at Detroit, in the county of Wayne and State of Michigan, have invented a certain new, original, and ornamental Design for a Belt, of which the following is a specification, reference being had therein to the accompanying drawing, forming a part thereof.

The figure on the drawing is a plan view of a belt showing my new design. The inner face of belt (not shown) is plain.

I claim:

The ornamental design for a belt, as shown and described.

JAMES SAMUEL ASHDOWNE.
